UNITED STATES PATENT OFFICE.

JOSEPH J. ABELSON, OF NEWARK, NEW JERSEY.

DESIGN FOR A RING.

51,687.

Specification for Design. Patented Jan. 15, 1918.

Application filed December 1, 1916. Serial No. 134,543. Term of patent 3½ years.

To all whom it may concern:

Be it known that I, JOSEPH J. ABELSON, a citizen of the United States, and a resident of Newark, in the county of Essex and State of New Jersey, have invented a new, original, and ornamental Design for a Ring, of which the following is a specification, reference being had to the accompanying drawings, which form a part of this specification.

Figure 1 is a front elevation of a ring illustrating my new design.

Fig. 2 is an edge view thereof.

I claim:

The ornamental design for a ring as shown.

JOSEPH J. ABELSON.
